CLAIM

The ornamental design for a computer cabinet, as shown and described.

DESCRIPTION

FIG. 1 is a front perspective view of the computer cabinet of the invention showing the overall profile as well as the movable tray thereof;

FIG. 2 is a front view of the computer cabinet of FIG. 1;

FIG. 3 is a right side view of the computer cabinet of the invention;

FIG. 4 is a left side view of the computer cabinet of FIG. 1;

FIG. 5 is a back view of the computer cabinet of FIG. 1; and, FIG. 6 is a bottom view of the computer cabinet of the invention.

The broken lines shown in the drawing are for illustrative purposes only and form no part of the claimed design.
